UNITED STATES PATENT OFFICE.

HARLAN GREGG, OF NASHUA, NEW HAMPSHIRE.

REGISTERING MEASURING-STAFF.

SPECIFICATION forming part of Letters Patent No. 316,353, dated April 21, 1885.

Application filed April 22, 1884. (No model.)

To all whom it may concern:

Be it known that I, HARLAN GREGG, a citizen of the United States, residing at Nashua, in the county of Hillsborough and State of New Hampshire, have invented new and useful Improvements in Registering-Measures, of which the following is a specification.

My invention relates to lumber-measures and similar devices which are used to determine the superficial area, in feet, of boards or other material, and it is the purpose thereof to provide such a measuring-staff with a registering mechanism by which the measurement may be registered, thereby avoiding the necessity of the operator carrying the several figures which represent the estimated area in his memory.

To this end my invention consists in the combination, with a lumber-measure or a similar measuring-staff, of a registering mechanism operated by a key, and imparting to one, two, or more registering-disks a rotary step-by-step movement, the arrangement being such that the disk registering the serial units or digits shall have action at each movement of the key until one complete revolution of said disk completes its limit of registration, when the next registering-disk is brought into action, and the succeeding enumeration registered thereby.

My invention further consists in means for locking the registering mechanism against all movement except when actuated by the operator.

My invention finally consists in the several features of construction and combinations of parts, fully set forth hereinafter, and definitely pointed out in the claims.

Referring to the drawings forming part of this application, Figure 1 is a longitudinal section taken through the end of the measuring-staff. Fig. 2 is a similar view illustrating the construction and combination of parts whereby, after the unit-disk has been rotated, the succeeding registration is automatically effected by the next succeeding registering-disk. Fig. 3 is a plan view, and Fig. 4 a detail perspective.

In the said drawings, the reference-letter A indicates the body of the measuring-staff, which may be of any suitable length and construction. In the body of this staff, and near

one of the ends thereof, convenient to the hand of the operator, I place a registering mechanism, of which the following is a description.

The ordinary lumber-measure is a staff of suitable length and dimensions, having the usual division into feet and inches. In practicing my invention I mortise a recess in one end, or near one end, of said staff, and place therein the registering mechanism, which may be journaled upon a plate, B, set in the recess or mortise on the staff. To this plate B is attached a second or face plate, C, arranged at right angles to the former, and having one, two, or more openings, a, formed therein, through which the registration of the disks may be seen.

Upon the plate B are journaled one, two, or more registering-disks, D D', &c., having such arrangement that their peripheries lie in the recesses a, formed in the plate C, thereby exhibiting through said openings the numbering upon the peripheries of said disks.

Near one end of said plate B, I pivot a bell-crank lever, E, having an arm, e, which projects through a slot, c, in the face-plate C, and is provided with a thumb-button, e'. Pressure upon the latter gives motion to the lower end in a line substantially parallel with the longitudinal axis of the staff.

Upon the lower edge of the plate B—that is, the edge opposite that upon which the face-plate C is mounted—are formed eyes or loops d d', within which slides longitudinally with the staff a plate, F, which is thrown in one direction by the bell-crank E, and in the opposite direction by a leaf-spring, f, mounted upon a stud, f', upon the plate B. This reciprocating plate carries a spring-pawl, G, which by its own elasticity engages with a ratchet, I, rigid upon the face of one of the registering-disks D. Upon the peripheral surface of this disk are formed the numbers, from one to a tenth space on the disk being occupied by the zero-mark or cipher, and each reciprocation of the plate F, which carries the spring-pawl, rotates the registering-disk D sufficiently far to present the next succeeding number upon its periphery to the opening a in the face-plate C. The disk D, as shown, is divided upon its periphery into ten equal portions, each bearing a numeral,

which may indicate the nine digits in succession; or each may represent a decimal enumeration. It will be seen that after the disk D has been rotated through nine-tenths of a single revolution a second disk must be brought into action in order to register those numerals in excess of the nine digits, the action of the second disk, D', being contemporaneous with the tenth step movement of the first disk, D, which is upon said movement brought back to the zero-point.

The second disk, D', is operated in the manner following: The said disk is journaled upon a stud, d', in such manner that its periphery, carrying the suitable numeration, is presented to the opening a in the plate C. Upon this face of the disk is rigidly mounted a ratchet, L, having teeth l, equal in number to the numbers upon the disk. Upon a lug, M, carried by the plate F, is pivoted a push-pawl, N, having its toothed end m extending over the ratchet L, and normally thrown toward said ratchet by a spring, m', mounted upon the plate F. The heel of the pawl, which is carried past the journal of the disk D, has a pin, n, which rests upon a flange, n', of the ratchet I, formed by cutting away the central portion of the disk D, on which the ratchet is formed. By reference to Fig. 1 it will be seen that as the plate F is thrown forward by the action of the bell-crank E the pin n, riding upon said flange, will hold the tooth of the pawl out of engagement with the teeth of the second ratchet, D', and the latter will therefore have no movement caused by said pawl. At a point upon said flange lying in substantially the same radius with the zero-space upon the disk D, I form a recess, n², of such dimensions that the pin n upon the heel of the pawl may at that point drop into said recess, and thereby cause its tooth m to engage with the ratchet L and rotate it throughout one-tenth of a revolution. It will be seen that this action of the pawl N can occur once only during each revolution of the registering-disk D, and that as the latter is at each movement of the plate F actuated in the manner described the tenth movement of the disk D will be accompanied by a simultaneous movement of the disk D', the former showing its zero-point in the opening a, and the latter exhibiting the initial figure in the series carried by it, or if such initial figure has been passed, then the one next properly succeeding. Both disks are held against rotation backward by spring-pawls i i', carried by the plate B.

In order to prevent the bell-crank E from being accidentally operated, I attach to the plate B a trigger, P, having one end projecting from the edge of the staff, and provided with a hook, p, upon its opposite end, which engages with a pin, b, upon the end of the bell-crank E. This trigger is normally thrown into engagement with the bell-crank by means of a leaf-spring, t, and when in such position it securely locks the registering mechanism from operation.

A stop-pin, g, is mounted upon the plate F, to limit the movement of the latter and prevent its pawls from carrying either one or both of the registering-disks more than one-tenth of a revolution at each reciprocation of the said plate.

The registering-disks may be operated by a slide instead of the bell-crank or angular lever shown, and the registering mechanism described may be applied to a variety of measuring devices wherein it is desired to register the measurement. The mechanism shown may, as set forth, be set in a mortise in the body of the rule or staff; or it may be mounted upon the outside, and the casing may be provided with a hinge, whereby access may be gained to the interior.

Three or more registering-disks may be used, the third and fourth, or either one, being actuated by a duplication of the mechanism substantially described hereinbefore, whereby the registration may run into figures of six or more places.

Any suitable form of lever may be substituted for the bell-crank or angular lever shown.

By my invention I provide a simple, easily-operated, and accurate recording mechanism, whereby many successive measurements may be registered, relieving the operator from all exercise of the memory, and giving a permanent and progressive record of a day's work.

In the drawings I represent the units of hundreds on the first disk, because a lumberman will usually carry in his head the number of feet to that amount; but it may as well represent units, or units of tens or of thousands. It is obvious that a friction device will essentially perform the functions of the springs i and i'.

If preferred, the sides of the disks may be shown and the figures placed on them near their peripheries.

What I claim as new, and desire to secure by Letters Patent, is—

1. The combination, with a measuring-staff, of a train of registering devices arranged within a recess in said staff, a lever pivoted in said recess and having engagement with a pawl-carrying plate, and a spring-actuated trigger which locks said lever, substantially as specified.

2. In a registering-measure, the combination, with a disk having suitable numbering upon its periphery, of a ratchet rigid with said disk, a pawl carried by a reciprocating plate and imparting a step movement to said ratchet, a flange upon the latter, having a recess, and a push-pawl having its heel supported by said flange and operating the second-disk once at each revolution of the first, substantially as described.

3. In a registering-measure, the combination, with a measuring-staff, of a series of registering-disks journaled in a chamber or recess in said staff, a ratchet formed or rigidly mounted upon the flat face of each disk, a slide-plate having a spring-pawl which actu-

ates the first disk at each reciprocation of said plate, a spring-actuated pawl pivotally mounted on said plate and having its heel supported by a flange on the ratchet of the first disk, 5 said flange having a recess nearly opposite the zero-point of the disk, and a lever pivoted in the recess of the staff and engaging with the slide-plate, whereby the second disk will be advanced a single space at each complete revolution of the first, substantially as specified.

4. In a registering-measure, the combination, with the numbered disks having ratchets equally toothed, of a reciprocating plate carrying a spring-pawl having successive action 15 upon one disk at each stroke of the plate, a push-pawl supported at one end by a recessed flange carried by the first disk, and having at each complete revolution thereof an operative engagement with the second disk, substantially as described.

20 5. In a registering-measure, the combination, with the registering-disks D and D', of the ratchets I and L, the former having a recess, n^2 , the reciprocating plate F, having

pawl G, the push-pawl N, carried by said plate, and having a pin, n , upon its heel, and means for reciprocating the latter, substantially as described.

6. In a registering-measure, the combination, with the peripherally-numbered disk D, 25 having a ratchet, I, provided with the flange n' and recess n^2 , of the reciprocating plate carrying a pawl, N, having its heel engaging with said flange, and a second disk, D', having ratchet L, substantially as described.

30 7. In a registering-measure, the combination, with the disks and a reciprocating pawl-carrying plate, of a pivoted lever, E, and a locking-trigger, P, having a hooked end, p, which engages with a pin upon the lever, substantially as described.

35 In testimony whereof I affix my signature in presence of two witnesses.

HARLAN GREGG.
